United States Patent Office

Des. 184,451
Patented Feb. 17, 1959

184,451

WRENCH

Robert E. Mullin, Independence, Mo.

Application July 10, 1958, Serial No. 51,731

Term of patent 14 years

(Cl. D54—16)

Fig. 1 is a plan view of a wrench embodying my new design;

Fig. 2 is a side elevational view of same;

Fig. 3 is an end view of same; and

Fig. 4 is an end view of same taken from the opposite end.

I claim:

The ornamental design for a wrench, as shown.
